US0D1087982S

(12) **United States Design Patent** (10) **Patent No.:** **US D1,087,982 S**
(45) **Date of Patent:** **** Aug. 12, 2025**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Gary William Gehiere**, Santa Clara, CA (US); **Amy Hung**, San Francisco, CA (US); **Daniel Huy Mai**, Cupertino, CA (US); **Jonathan Cho**, San Francisco, CA (US)

(73) Assignee: **Apple Inc.**, Cupertino, CA (US)

(**) Term: **15 Years**

(21) Appl. No.: **29/863,407**

(22) Filed: **Dec. 19, 2022**

Related U.S. Application Data

(63) Continuation of application No. 29/758,325, filed on Nov. 13, 2020, now Pat. No. Des. 976,948, which is a continuation of application No. 29/684,768, filed on Mar. 23, 2019, now Pat. No. Des. 902,235.

CLAIM

The ornamental design for a display screen or portion thereof with graphical user interface as shown and described.

DESCRIPTION

The sole FIGURE shows a display screen or portion thereof with graphical user interface showing our new design. The peripheral dashed broken lines illustrate a display screen or portion thereof, and form no part of the claimed design. The broken lines within the peripheral dashed broken lines illustrate portions of the graphical user interface which form no part of the claimed design.

1 Claim, 1 Drawing Sheet
